UNITED STATES PATENT OFFICE.

CHARLES F. KETTERING, OF DAYTON, OHIO, ASSIGNOR TO THE DAYTON ENGINEERING LABORATORIES COMPANY, A CORPORATION OF OHIO.

ENGINE STARTING, LIGHTING, AND IGNITION SYSTEM.

1,254,811.

Specification of Letters Patent. Patented Jan. 29, 1918.

Original application filed April 17, 1911, Serial No. 621,512. Divided and this application filed April 19, 1915. Serial No. 22,310.

To all whom it may concern:

Be it known that I, CHARLES F. KETTERING, a citizen of the United States of America, residing at Dayton, county of 5 Montgomery, and State of Ohio, have invented certain new and useful Improvements in Engine Starting, Lighting, and Ignition Systems, of which the following is a full, clear, and exact description.

10 This invention relates to a system of devices adapted for supplying power to start an engine, and the engine when thus started is arranged to store up power for similar starting operations; and this same power 15 source may then be used for the ignition system of the engine, and to furnish a lighting circuit.

That is, in the particular form hereinafter 20 described as embodying my inventions, I have provided an automatic starting device for automobile engines, so as to eliminate the manual cranking of the engine. The power to start, or crank the engine in this 25 automatic manner is derived from electric storage batteries, which supply current to an electric motor that is connected to the engine. Then after the engine has been thus started, it operates the electric motor as a generator to supply electric current, which 30 is stored up in any suitable storage batteries.

The present application is a division of my co-pending application, Serial No. 621,512, filed April 17, 1911, which eventually 35 resulted into Patent 1,171,055, dated February 8, 1916.

Some of the mechanisms shown in the present application, form the subject matter of claims in my application just referred 40 to. The improvements of the present application refer to the mechanical arrangements associated with the starting and with the generating apparatus above referred to.

For example, it is among the objects of 45 the present invention to provide means for preventing the reengagement of the gears between the motor and the engine, after the motor has started the engine and the gears have been disengaged, this being effective 50 until the engine has substantially stopped. The gears referred to in the present case

constitute all of the mechanical connections between the electric motor and the engine.

Other improvements shown in the present application relate to locking devices for 55 connection with the starting lever, and also some adjusting devices connected with the starting lever for adjusting the timing device and the gasoline carburetor into their most advantageous positions for starting. 60

Further objects and advantages of the present invention will be apparent from the following description, reference being had to the accompanying drawings, wherein a preferred form of embodiment of the invention 65 is illustrated.

In the drawings:

Figure 1 is a top plan view of the chassis 70 of an automobile to which my improvements are applied. Certain parts of the chassis 75 of the automobile are removed for the sake of clearness, the portion of my improvements shown therein being more particularly the motor-generator and its connections to the engine.

Fig. 2 represents a side elevation of the engine and flywheel of this automobile, showing the motor-generator with the gearing connections and the flywheel ready for starting.

Fig. 3 is a fragmentary detail view of the motor fly-wheel gearing.

Fig. 3^a is a front end view of the timing gears of the engine showing the driving connection thereof with the motor generator 85 shaft, whereby the motor generator is driven as a generator by the engine.

Fig. 4 is a detail side view of the parts shown in Fig. 3, with the exception that the flywheel is removed for the sake of clearness.

Fig. 5 is a detail view of the friction clutch carried by one of the transmission pinions of the motor flywheel gearing.

Fig. 6 is a sectional view of Fig. 5.

Fig. 7 is a detail view of the cooperating locking elements of the transmission control lever and the foot pedal device.

Referring now to Fig. 1, it may be stated that the type of automobiles in which these 100 improvements are shown as applied, is the "Cadillac," which is a well known auto-

mobile on the market at the present time. In this view, the chassis is shown having the side frames 30 and carrying the engine 31 which is of the four-cylinder type ordinarily used in automobiles. 32 are the front wheels, and 33 the running boards. 34 is the box containing the transmission gears, and 35 is the transmission lever, which when moved back and forth controls 10 the selection of the transmission gears in a well known manner, one position being the neutral, in which the engine driving shaft is not connected up to the driving wheels of the automobile; and the other positions of 15 the control lever 35 operating the transmission gears to produce the various speeds forward or the reverse speed.

36 is a casing containing the ordinary oil pump such as is customarily used on a car 20 of this type. This oil pump is operated by a shaft 37 which is utilized in connection with the present inventions as will appear hereinafter.

38 is the flywheel of the engine, connected 25 of course directly with the engine shaft. 39 is the clutch disk, the usual form having the conical shaped periphery which engages in the interior of the flywheel and may be operated as by a pedal 40 to be thrown into 30 and out of engagement with the flywheel in a well known manner to make or un-make the connection between the engine and the transmission gears.

41 is the motor-generator forming part of 35 the present improvements and arranged to serve as a motor to start the engine and as a generator to charge the storage batteries. This motor-generator is controlled as to its status as a motor or as a generator, by the 40 foot pedal 42, mounted upon a cross rock shaft 43. From this rock shaft 43 there extends upward an arm connected to a link 44 which extends forward to control the gearing connections between the motor- 45 generator and the engine. Another link 45 extends rearward and is connected to a bell crank lever 46 which in turn is connected by a link 47 to the switch or controller 48 shown diagrammatically in dotted lines in 50 Fig. 1. This controller 48 is contained within a casing or box 49 which is carried upon the running board of the car and is intended to be a convenient place to carry also the storage batteries and other appurte- 55 nances of this electrical system.

These various connections will be described more in detail later, but in general it may be seen from Fig. 1 that the operation of the foot pedal or starting pedal 42 60 operates through the link 44 to control the connections between the engine and the motor-generator, and through the link 45 to operate the electrical switch or controller which governs all of the electrical circuits 65 as will hereinafter appear.

The connections between the engine and the motor-generator will now be described.

Referring to Fig. 3^a, the engine shaft 50 carries a small gear 51. This meshes on one side with a gear wheel 52 which in a well known manner is used to operate cams which move the valve stems 53 for the respective cylinders 54 of the engine, but as these parts form no portion of the present improvements, no further description of them will be given.

The gear 51 also meshes with an intermediate gear 55 which transmits motion to its intermeshing small gear 56 which is fast upon the aforesaid shaft 37 see Figs. 1 and 2 which heretofore has been utilized to operate a magneto for ignition purposes. Because of the previous existence of a shaft of this sort, in a car of this type, it is found advantageous to use this as one connecting means for one set of gearing between the engine and the motor-generator.

Referring now to Fig. 2, it will be seen that the said shaft 37 carries a shiftable clutch member 60, having teeth adapted to engage with the corresponding clutch member 61 which is fast upon the shaft of the armature of the motor-generator 41. This shifting clutch member 60 is operated by a central pivot lever 62 which is connected to an arm 63, extending rearward to an arm 64 (see also Fig. 1). This arm 64 is pivoted at its middle point, the outer end of the arm being connected to the aforesaid link 44 shown in Fig. 1, and the inner end 100 of the arm being connected to the rod 63.

Thus it will be apparent that the operation of the foot pedal 42, when pressed forward, throws the link or rod 44 forward, which retracts the rod 63 rearward and thereby moves the clutch member 61 out of engaging position so that it rests in the position shown in Fig. 2.

This is the starting position. That is, it is intended that the pressing forward of the foot pedal or starter pedal 42, shall prepare for the starting of the engine by the electric motor; and upon the return of the pedal to normal rearward position, the connections are such as to have the motor-generator operate as a generator. In such case, the return of the foot pedal 42 to normal rearward position would throw the rod 63 forward, thus engaging the clutch member 60 with its companion member 61. This makes a direct connection between the engine shaft 50 (Fig. 3^a) through the counter-shaft 37 and clutch members 60 and 61, directly with the armature of the motor-generator.

It will be seen that the size of these connecting gears is such that the armature of the motor-generator would in this charging position be driven at the same speed as the engine shaft 50. That is, the generator is 130

driven, for charging purposes, at engine speed.

I will now describe the connections between the engine and the motor-generator for the starting position, that is, when the motor-generator is operating as a motor.

As seen in Fig. 2, the end of the armature shaft 65, of the motor-generator, carries a pinion 66. The flywheel 38 is formed upon the forward parts of its periphery with gear teeth 67. There is a shifting gear arrangement so arranged that these gears will connect up the motor pinion 66 to the gear teeth 67 of the flywheel, or said gears may be shifted laterally so as to break this gearing connection.

The exact construction of these parts is shown more clearly in Figs. 3 and 4. A stub-shaft 70 projects from the framework 20 of the motor-generator, being at its outer end suitably supported by a framework 71. Mounted to slide or shift laterally upon this stub-shaft are two gear wheels 72 and 73 which are arranged to be clutched together in a manner to be presently explained.

The gear wheel 72, which is the larger of these two, is arranged to mesh with the motor pinion 66; while the smaller gear wheel 30 73 is arranged to mesh with the teeth 67 of the flywheel 38.

The device for shifting these gear wheels 72 and 73 forwardly and rearwardly on the shaft 70 comprises a yoke 74 which projects 35 into an annular groove formed in the sleeve 75 extending from these gear wheels. This yoke is fast to a hub 76 which is pinned to a shaft 77, which extends forward from a similar hub which is the center part of the 40 aforesaid arm 64 which is operated by the starter pedal 42.

Thus, when the starter pedal is pushed forward so as to throw the connecting rod 44 forward, this rocks the arm 64 and thereby turns the aforesaid short shaft 77 so as to move the yoke 74 rearward (to the left in Fig. 4). This shifts the intermediate gears 72 and 73 to the left in Fig. 4, and brings the gear 72 into mesh with the motor 50 gear 66 as seen in the position shown in Fig. 4. In this position the gear wheel 73 is meshing with the teeth 67 of the flywheel 38. In Fig. 4 the flywheel is shown removed for the sake of clearness, but the 55 position can readily be seen from Fig. 3.

Now, when the starter pedal 42 is allowed to return to its normal position, this shifts the gear wheels 72 and 73 to the right in Fig. 4, and withdraws the gear 72 from meshing 60 with the motor pinion 66 and also withdraws the gear 73 from engagement with the teeth of the flywheel.

Now, when the parts are in the position shown in Fig. 4, which is the starting position, the ratio of the gearing is a multiplied

ratio, that is, the motor pinion 66 can revolve at a fairly high rate of speed, but the flywheel of the engine moves comparatively slowly so that thereby the motor may revolve rapidly and the engine may be cranked 70 slowly by the motor for the purpose of starting.

As seen above, when the starter pedal 42 returns to normal rearward position, the gearing connection between the motor pinion 75 66 and the flywheel is broken by the shifting of the gears 72 and 73, and the other connecting gearing between the engine and motor-generator is brought into play, that is, the one to one ratio gearing, through the 80 medium of the clutch members 60 and 61, which drive the motor-generator from the engine as a generator.

Usually it will be possible to make the gear wheels 72 and 73 go into mesh respectively with the pinion 66 and gear teeth 67, but if these gears happen to be out of proper alignment for enmeshment upon this proper shifting, the initial movement of the motor pinion 66, by reason of the starting up of 90 the motor current upon the shifting of the starter pedal (as later explained), would give the motor pinion enough movement to start to pick up these gears and permit the lateral shifting. Or if desired, some auxiliary device could be utilized to give the motor a slow turning movement preliminary to the shifting of these gears for enmeshment. Such a device forms the subject matter of another pending application filed 95 100 by me.

It has just been stated above that the two gears 72 and 73 were arranged to be clutched together in order to turn the flywheel by revolution of the motor shaft pinion 66. 105 This clutch mechanism is shown in Figs. 5 and 6, and is of a well known form.

Loosely mounted upon the aforesaid stub-shaft 70 is the said gear wheel 73 which has a laterally extending collar 80 over 110 which is fitted a tooth shaped cam disk 81, the shape of which is clearly shown in Fig. 5. This disk 81 is pinned to the gear 73 by pins 82. In the recesses between the disk 81 and the inner periphery of the gear wheel 115 72 are friction rollers 83 which are normally spring-pressed away from the disk 81 by springs 85.

When the gear wheel 72 rotates in the direction of the arrow in Fig. 5, which is the 120 direction of rotation under which it is driven when the motor revolves for starting, the friction of the inner periphery of the gear wheel 72 carries the rollers 83 into the V-shaped portions of the recess between the 125 disk 81 and the gear 72. This causes the gear 72 to drive the disk 81 and thereby drive the pinion gear wheel 73. This in turn drives the flywheel, as is obvious from Fig. 3.

If the motor is thus brought to drive the flywheel and start the engine, then as soon as the engine starts, it will naturally tend to revolve faster than the motor would tend to drive it. In this case the gear 73 is now driven by the engine, thus driving the disk 81 and resulting in the friction rollers 83 occupying the enlarged portions of these slots in which they reside. This prevents any friction grip upon the gear wheel 72, so that the disk 81 and gear wheel 73, and the flywheel of the engine can all revolve faster than the gear 72 while the gear 72 is driven slowly by the motor, so long as the motor is running under its own current. This permits the engine to run ahead of the motor as soon as it has started.

I have also arranged a preventing means which prevents the reengagement of the gear wheel 73 with the flywheel, after the engine has been started and the gears have been disengaged. By referring to Fig. 4, it will be seen that the end of the motor shaft 65 carries a governor 90 against the end of the movable portion of which rests a blocking lever 91, pivoted at 92 to a portion of the framework. The upper end 93 of this blocking lever rests in a slot in the end of the shaft 70 and is of such length that when the yoke 74 is moved to shift the gear wheels 73 and 72 to the right in Fig. 4, the inner end of this portion 93 of the blocking lever, tends to spring up (under tension of spring 94), into dotted line position, so that the end of the lever will abut against the outer end of the sleeve carrying the gear 72, and thus block the movement of the gear wheel 73 to the left.

This movement of the blocking lever is permitted when the motor has got up to speed, so that the governor balls separate and permit the arm 91 of this lever to spring inward. Thereupon, as soon as the operator restores the starting pedal to normal position, thereby shifting the gears 72 and 73 out of mesh with the flywheel, this blocking lever then prevents the gears from being shifted back again.

Thus the result is that after the motor has started the engine, and the engine flywheel has got up to speed, then if the operator returns the starter pedal to normal position and disengages the gear 73 from the flywheel, these parts cannot again be engaged until the motor has stopped or slowed down to slow speed. This prevents injury to the gears by trying to force them into mesh when running at too high a speed.

In Fig. 7 is shown the device which prevents the starter pedal 42 from being actuated when the transmission control lever occupies any position other than its neutral position. Extending downward from the rock shaft 43 is an arm 100 to which is attached a gear rod 101. The transmission

control lever 35 has attached to it a locking plate 102 formed with a slot 103. The position shown in Fig. 7 represents the neutral position of the transmission lever 35, wherein the transmission gears are disconnected, 70 that is, the engine is disconnected from the wheels of the automobile. In this neutral position, the slot 103 is opposite the locking rod 101, so that the starter pedal 42 is free to be operated, and when so operated by being 75 pushed forward, the locking rod 101 enters the slot 103, thereby locking the transmission lever so that the transmission cannot be moved during this process of starting.

It likewise follows that the locking plate 80 102 blocks the movement of the rod 101, when the lever 35 is out of normal position, so that the starting pedal 42 cannot be pushed forward for starting the engine, when the lever 35 is at any other place than 85 neutral position. A spring 104 operates upon the pedal 42 to normally tend to bring the pedal back to rearward position.

While the form of mechanism herein shown and described constitutes a preferred 90 form of embodiment of the present invention, it is to be understood that other forms might be adopted all coming within the scope of the claims which follow.

What I claim is as follows:

1. In an engine starting device, the combination with an engine, of a starting device therefor; means for operatively connecting said starting device to said engine; and means actuated by said engine for preventing the connection of the starting device as such to the engine, once it has been disconnected and the engine is operating under its own power.

2. In an engine starting device, the combination with an engine, of a starting device therefor; means for operatively connecting said starting device to said engine; and mechanical means for preventing the connecting of the starting device as such to the 110 engine, once it has been disconnected and the engine is operating under its own power.

3. In an engine starting device, the combination with an engine, of a starting device therefor; means for operatively connecting 115 said starting device to said engine; and a centrifugal governor controlled by the operation of said engine for preventing the connection of the starting device as such to the engine, once it has been disconnected 120 and the engine is operating under its own power.

4. In an engine starting device, the combination with an engine, of a starting device therefor; connecting means including 125 meshing gears axially movable for operatively connecting said starting device to said engine; and means controlled by the speed of the engine for preventing the axial movement of said gears to connect the starting 130

device as such to the engine, once it has been disconnected and the engine is operating under its own power.

5. In an engine starting system, the combination with an engine and a starting device therefor, including an electric motor having an armature shaft; shiftable intermediate gearing for connecting said armature shaft and engine for starting purposes; 10 and means controlled by the speed of the engine for preventing the movement of the shiftable gearing to connect the engine and starting device together, when the engine and starting device have once been disconnected and the engine is self-actuating.

6. In a starting device for vehicles, the combination with an engine, an electric motor, and intermediate connections between the engine and the electric motor for starting the former by the latter; of a vehicle upon which said engine and electric motor are mounted; driving connections between said engine and the running gear of said vehicle; means for coupling and uncoupling said engine and said driving connections; and means for preventing the connections between the engine and electric motor from being established when said coupling means is in operative position to connect the engine 25 with said driving means.

7. In a starting device for vehicles, the combination with an engine, an electric motor, and intermediate connections between the engine and the electric motor for starting the former by the latter; of a vehicle upon which said engine and electric motor are mounted; driving connections between said engine and the running gear of said vehicle; means for coupling and uncoupling 30 said engine and said driving connections; and means for preventing the connections between the engine and the electric motor from being established when said coupling means is in operative position to connect the engine 35 with said driving means; with provisions for also preventing the movement of said coupling means when the latter is in the uncoupling position and the said intermediate connections are in operative position connecting the motor-generator with the engine for starting.

8. In an engine starting device, the combination with an engine, of a dynamo electric machine for starting the engine; two independent sets of connections between the electric machine and the engine; and an operating member for controlling said connections, constructed to break the first of said connections when the second connection is 40 established for starting the engine by the electric machine, and vice versa establishing said first connection to thereby drive the electric machine from the engine when the aforesaid second or starting connection is 45 broken.

9. In a device of the character described, the combination with an engine, an electric motor, intermediate connections between the engine and electric motor for starting the former by the latter, and an operating member for controlling said intermediate connections; of means for preventing the operation of said operating member to reengage said intermediate connections between the engine and electric motor after the latter has 50 started the former and the said connections have been broken.

10. In a device of the character described, the combination with an engine, an electric motor, intermediate connections between the engine and electric motor for starting the former by the latter, and an operating member for controlling said intermediate connections; of a governor connected with said engine; and means connected with said governor for preventing the operation of said operating member to reengage said connections between the engine and electric motor after the engine has been started and is running at speed and said connections have been 60 disengaged.

11. In combination with an internal combustion engine, a starter comprising a motor, power transmitting mechanism between the engine and motor comprising two members 65 one of which is movable into and out of engagement with the other, mechanism adapted to be shifted by the operator for establishing driving relation between the motor and engine, and means for rendering said 70 mechanism inoperative when the engine is in operation.

12. The combination with an engine having a shaft, a starting motor, and means for operatively connecting said motor to said 75 shaft, of means controlled by centrifugal force for preventing the establishment of said operative connection.

13. The combination with an engine having a shaft, a starting motor, and means for operatively connecting said motor to said 80 shaft, of speed-controlled means for preventing the establishment of said operative connection.

14. The combination with an engine having a shaft, a starting motor, and means for operatively connecting said motor to said 85 shaft, of locking means for preventing the establishment of said operative connection, and means controlled by centrifugal force 90 for actuating said locking means.

15. The combination with an engine having a shaft, a starting motor, means for operatively connecting said motor to said shaft, of locking means for preventing the establishment of said operative connection, and speed-controlled means for actuating said 95 locking means.

16. The combination with an engine having a shaft, a starting motor, means for op- 100

eratively connecting said motor to said shaft, of locking means for preventing the establishment of said operative connection, and means for actuating said locking means when 5 the engine operates under its own power.

17. In combination, two gear wheels, one of which is relatively shiftable into and out of mesh with the other, and mechanical means which automatically prevents the 10 meshing of said gear wheels when one of them is rotating.

18. In combination, two gear wheels, one of which is shiftable into and out of mesh with the other, and mechanical means for 15 locking said shiftable gear wheel in an inop-

erative position upon an attempt to mesh said gear wheels when one of them is rotating.

19. The combination with two gear wheels, one of which is relatively shiftable into and 20 out of mesh with the other, of means for automatically preventing the meshing of said gear wheels when one of them is rotating.

In testimony whereof I affix my signature in the presence of two subscribing witnesses. 25

CHARLES F. KETTERING.
